UNITED STATES PATENT OFFICE

ANDRÉ LEYVRAZ, OF LAUSANNE, SWITZERLAND, ASSIGNOR TO WALDO MAAS, OF LONDON, ENGLAND, AND FRANK GRINSTEAD, OF DURRINGTON, ENGLAND

ELECTRIC WRITING MACHINE

Application filed December 15, 1927, Serial No. 240,276, and in Switzerland December 14, 1926.

This invention relates to electrically operated type-writing machines of the type comprising a single electro-magnetic motor device producing the striking or impression of all the individual characters of the type, and electro-magnetic devices for selecting the characters the impression of which is to be produced by the said first device the electro-magnetic selection devices actuating movable members effecting the actual selection and operation of the type-carrying levers or bars.

The annexed drawing illustrates an example of construction of the machine.

15 Fig. 1 is a partial plan view.

Fig. 2 is a vertical longitudinal section on the broken line II—II of Fig. 1.

Figs. 3 and 4 illustrate a detail of the magnetic striking device.

20 Each of the type-carrying levers or bars 1 is pivoted on a curved rod 2, common to all, and is normally in the horizontal position of rest shown in Fig. 2, but can be brought into the position shown in dotted lines in this

25 figure where the impression is to be made. To this effect, each lever or bar 1 is provided with a toothed sector 3 gearing with a rack 4 which can move horizontally backwards and forwards in the machine that is to say 30 from right to left or from left to right in Fig. 2 the racks being guided on two semi-circular rods 5, common to all the racks, and passing through guide slots 6 of the latter. The displacement of a rack towards the left in Fig. 2

35 for the purpose of operating the impression of a character is effected by means of a finger 7 which can move horizontally and vertically, and to which the electro-magnetic impression or striking device 8 imparts a movement to 40 the left (Fig. 2). This finger comes into engagement with a nose 9 of the rack 4 when it is raised by the action of the corresponding electro-magnetic selection device 10. The displacement of the rack 4 in the opposite

45 direction is produced by a helical traction spring 11 connected at one end to the nose 9 and at the other end to an angle bar 12, the vertical arm of which is longer than the horizontal arm thereof.

50 The angle bar 12 is made of magnetic ma-

terial, of soft iron for example. The electro-magnetic selection devices 10 consisting of electro-magnets, each comprise an angle bar 12 the horizontal arm 13 of which supports the core 14 of the coil 15, the vertical part 16 of the angle bar carries the pivot 17 on which the armature 18 is pivoted. As can be seen from Fig. 2 the gap of the magnetic circuit of the electro-magnet is relatively small so that the latter functions under good conditions. A spring 19 maintains the armature 18 in its lowered position. Each electro-magnet is fastened to a common support 100 to which is also fixed a bed 29 to which the ends of the conductors of the various coils 15 are connected and from which lead conductors leading to the operating keys (not illustrated).

When one of the electro-magnets 10 attracts its armature 18 the latter lifts the corresponding finger 7 which slides vertically in a guide bar 21 curved to an arc of a circle and supporting all the fingers 7.

The guide bar 21 is fixed to a carriage 22 given horizontal movement by the electro-magnetic device 8. When the finger 7 is raised this horizontal movement is communicated to the rack 4 which then produces the impression of the corresponding character. The finger 7 is submitted to the action of a traction spring 24 and its movement is limited by 70 abutment pins 25, it is of square section and moves and is guided in apertures of corresponding shape in the guide 21 so that it cannot turn on itself and acts always with one of its faces on the nose 9.

The carriage 22 is connected rigidly by an arm 30 to a crosspiece 31 constructed of a magnetic metal and to which are fixed the movable cores 32 of two solenoids 33 constituting the electro-magnet impression or striking device 8; each of the cores 32 can slide on a guide rod 34 of non-magnetic metal.

The solenoids 33 contain fixed cores 37 which are integral with a common block 35 the said fixed cores being provided at the ends adjacent the movable cores 32 with trunconical cavities 36, the cores 32 having similar cone shaped ends. This arrangement pro-

vides for the strongest and most rapid attraction of the movable cores.

A traction spring 40 normally maintains the cores 32 separated from the fixed cores 37.

5 The operation is as follows:

When one of the keys (not shown) is depressed the circuit of the corresponding electro-magnet 10 and of the solenoids 33 is closed.

10 The electro-magnet 10 lifts its armature 18 and causes the finger 7 to rise so that its upper part is opposite the nose 9. As the solenoids 33 then cause the guide 21 to move from right to left, the finger 7 strikes the nose 9 15 and the lever 1 strikes the paper on the roller (not shown on the drawing). The impression being effected and the key released the springs 11, 19 and 24 return the various parts to their position of rest.

20 As there is only a single electro-magnetic striking or impression device, it can be given such dimensions that it will produce an energetic striking. This electro-magnetic device may have further functions such as operating 25 the advance of the roller carriage actuating the linking ribbon, etc. The electro-magnets 10 can however be of very small dimensions, as they have only to furnish slight power. Further each of them is fixed and the electro- 30 magnetic striking or impression device, instead of having to displace all the electro-magnets 10 has only the guide-bar 21 to move and the fingers 7 which it carries, this guide bar being lighter than the squares 12 and the 35 parts which are connected thereto.

The electro-magnets 10 could be replaced by solenoids and the solenoids 33 by one or more electro-magnets.

The machine can be provided with one or 40 more characters per type lever.

What I claim as my invention and desire to secure by Letters Patent of the United States is:—

1. In an electrically operated typewriting- 45 machine the combination of a series of type bars, a corresponding series of selecting electro-magnets associated with said bars, a second electro-magnetic device, a series of slidably mounted fingers associated with said type bars, the said fingers being slidable independently in an axial direction by said selecting electro-magnets and collectively in a direction transversely of their axes by said second electro-magnetic device, racks having 50 projecting parts on which said fingers in their movement transversely of their axes operate to move said racks in one direction, toothed sectors integral with said type bars actuated by said racks, and springs adapted to return said racks and thereby said type-bars to the 55 normal position.

2. An electrically operated typewriting- 60 machine according to claim 1, wherein the fingers slide in the course of their axial movements in a guide which is common to all and

to which movement is imparted by the second electro-magnetic device for moving the fingers collectively, whatever be their position relative to the guide substantially as described.

In witness whereof I have signed this 70 specification.
